UNITED STATES PATENT OFFICE

2,684,252

SKI POLE CARRIER

Charles Harvey Churchill, Cortland, N. Y.

Application July 6, 1950, Serial No. 172,328

1 Claim. (Cl. 280—11.37)

1

This invention relates to a fastener for securing skis and ski poles together.

An object of my invention is to provide a fastening device applicable for securing skis and ski poles together in compact assembled relation to facilitate carriage and storage thereof.

Another object of the invention is to provide a ski and ski pole fastener of the above mentioned character which will cover and thereby protect the spiked or tapered point tip of ski poles when being carried and also prevent personal injuries which might otherwise be inflicted by coming into contact with the point tips during handling of the skis and ski poles. Still another object of the invention is to provide a ski fastener of the above character which is equally applicable for skis and ski poles of various sizes whether for men, women or children.

A further object of this invention is to provide a ski fastener of theforesaid character which may be quickly and easily applied to the skis and ski poles or removed therefrom.

Still further objects reside in the provision of a ski and ski pole fastener which is light in weight, relatively simple and durable in construction and which may be folded in to a relatively small compact package when not in use.

Other objects and advantages pertaining to the detailed construction and to the form and relation of the parts thereof will be apparent from the following description taken in confirmation with the accompanying drawings in which:

Figure 1 is a perspective view showing a pair of skis and ski poles secured together with my improved fastener.

Figure 2 is a perspective view of my ski and ski pole fastener shown in Figure 1 on an enlarged scale.

Figure 3 is a transverse sectional view on an enlarged scale taken substantially in the plane of line 3—3 Figure 1.

Figure 4 is a side elevation of Figure 1, partly in section.

Figure 5 is an inverted perspective view of one of the ski poles tip shields.

Figure 6 is a perspective view showing a modified form of my ski pole tip shield as shown in Figures 2 and 5.

Figure 7 is a perspective view showing a modified form of my ski pole tip shield as shown in Figures 2 and 5.

Figure 8 is a perspective view showing a modified form of my ski pole tip shield as shown in Figures 2 and 5.

Figure 9 is a perspective view showing a modi-

2

fied form of my ski pole tip shield as shown in Figures 2 and 5.

The preferred embodiment of my invention as shown in Figures 1 to 5 inclusive comprises a pair of tubular shields 10 for the spiked or pointed tips 11 of a pair of ski poles 12. Each shield 10 is preferably rectangular in cross section and of such a length as to extend longitudinally of the pole 12 from the tip 11 thereof to a position intermediate said tip and a snow ring 13 secured to the pole 12 in the usual manner as by flexible attachment means or webbing 14. The bottom 15 of each shield 10, in this instance, is provided with a pair of elongated recesses 16 near one end thereof. The recesses 16 are arranged in substantially parallel spaced relation to each other transversely of the bottom 15 for the reception of a flexible strap 17 therethrough. The end of the shield 10 adjacent recesses 16 is preferably closed as by bending an extended portion 15' of the bottom 15 upwardly. The end 15' is extended a short distance above the top 18 of the shield and is provided with an elongated recess 19 which extends transversely thereof adjacent its outer end for the reception of a pole retaining flexible strap 21.

The device described above is used as follows:

A pair of skis S are first disposed in bottom to bottom longitudinally extending positions. A strap 17 having a pair of shields 10 threaded thereon, as shown in Figure 2, is now wrapped about the skis adjacent the forward ends thereof with the shields 10 arranged longitudinally against the outer sides of the skis. The strap 17 is preferably of such length as to be wrapped twice around the skis, once in the plane of the shields recesses and once in a plane just forward of said shields. The buckle 23 of strap 17 is preferably of the slip type so that the strap may be tightly fastened about skis of any width. Furthermore, it will be observed that the shields 10 may be readily adjusted longitudinally of the strap 17 by sliding the strap through recesses 16. This provides for the shields 10 to be easily positioned substantially midway between the sides of the respective ski as the strap is being applied to the skis.

After the skis have been thus securely fastened together, the ski poles 12 are arranged adjacent the outer sides of the skis longitudinally thereof and with the spiked or pointed tip ends 11 thereof inserted into a respective shield 10. The poles 12 are next secured in position by straps 21 which are passed through the respective recesses 19 and 55 around the corresponding snow rings 13 as clearly

illustrated in Figure 4. Strap 21, like strap 17 is preferably provided with a buckle 25 of the slip type so that poles of different structures may be tightly fastened to the shields with the tips 11 of the poles abutting against the closed ends 15 thereof. The other or upper ends of the poles 12 and the adjacent portion of the skis S may now be secured together by a strap 26 as shown in Figure 1. In Figures 6, 7, 8 and 9 I have illustrated certain modifications of the shield 16 shown in the preceding view of the drawings. For instance, in Figure 6, the shield 28 has the extended bottom 29 thereof folded back to form a loop 30 arranged forwardly of the end wall 31 through which the strap 17 may be passed. A rivet or bolt 32 may be passed through the folded portions of the bottom 29 at the inside of the loop 30 to strengthen the structure.

In Figure 7 the shield 35 has its bottom wall 36 extended beyond the closed end thereof and provided with a pair of elongated recesses 37 arranged in spaced substantially parallel relation transversely thereof for the reception of the strap 17. In this instance the upper wall 33 of the shield 35 is provided with a bent up portion 38 having the elongated recess 19 for the reception of strap 21. Also one of the side walls 41 has a portion 41' extended over the bottom portion 36 to form an end wall for the tube against which the spiked or tapered end 11 of the ski pole 12 may abut.

In Figure 8 the shield 43 has the bottom 44 extended vertically at 44' and provided with the elongated recess 19. However, this extension 44' is spaced forwardly of the adjacent end of the shield 43 to provide the space 45 therebetween for the reception of a retaining plate 46. The plate 46 has an elongated recess 47 extending transversely adjacent one end thereof for the reception of the extension 44' therethrough. Forwardly of recess 47 are the two recesses 37 for the reception of strap 17 as in Figure 7.

In Figure 9 the shield 50 is circular in cross section and has one end thereof collapsed to form a feather 51. A rivet, bolt or the like 52

extending through a suitable hole in projection 54 connects the shield to one end of a retaining plate 56. Adjacent the other end of plate 56 are the two bolt receiving recesses 37. The plate 54 is also provided with a vertical extension 55 arranged intermediate recesses 37 and the projection 51 which has the bolt receiving recess 16 adjacent the upper edge thereof.

The shield structures shown in Figures 6 to 9 inclusive may each be secured to the skis in the manner hereinbefore described for the shield shown in Figures 1 to 5 inclusive.

Although I have shown and described the preferred embodiment of my invention and certain modifications thereof it is obvious that other changes as to shape, size and arrangement of parts thereof may be made without departing from the spirit of the invention or scope of the appended claim.

I claim:

A fastening device for a pair of skis and a pair of ski poles of the character described comprising in combination, a strap adapted to be wrapped around the skis, a pair of tubular shields adapted to receive respective tip point portions of the ski poles therein, means securing the strap and shields to each other with said shields arranged in spaced relation longitudinally of said straps, and separate means including a pair of additional straps engaging the snow rings of the ski poles and the shields for removably securing the ski poles and shields to each other.
